UNITED STATES PATENT OFFICE.

EPPA H. RYON, OF PASADENA, CALIFORNIA, ASSIGNOR TO CROMPTON & KNOWLES LOOM WORKS, OF WORCESTER, MASSACHUSETTS, A CORPORATION OF MASSACHUSETTS.

COLOR INDICATOR FOR WEFT-REPLENISHING LOOMS.

Application filed October 4, 1926. Serial No. 138,968.

This invention relates to improvements in color indicating mechanisms for automatic box looms and it is the principal object of the invention to provide a color indicator for looms employing the Knowles head wherein the indication will be given earlier than has been possible heretofore.

Multi-color weft replenishing looms usually employ a magazine in which the bobbins 10 are arranged in parallel stacks according to distinctive characteristics and there is usually employed a sliding and angularly movable color selector which cooperates with a plurality of bobbin releasing devices. The selector moves to any one of several positions depending upon which shuttle is active and receives an angular movement at the proper time either to initiate replenishment or to advance the bobbin from the stack toward a 20 transfer position common to all the stacks. In this latter operation it is desirable that as much time as possible be given the bobbin to move toward transfer position.

Worsted looms are ordinarily equipped 25 with the so-called Knowles head to actuate the boxes and run at a sufficiently slow rate of speed so that the color selector can be connected directly to the box actuating mechanism, but where faster running looms 30 are equipped with the Knowles head it is found that insufficient time elapses between the releasing of the bobbin from the stack and its arrival in transfer position, the bobbin frequently being caught before being 35 properly placed by the descending trans- ferrer arm and either crushed or improperly inserted in the shuttle. It is an important object of my invention to provide an actuator for the color slide deriving its motion 40 from some part of the Knowles head which moves in advance of the boxes. As shown herein I have provided a set of compound levers actuated by the vibrator levers which are lifted by the pattern chain of the head. 45 motion, but I do not wish to be held to this particular source of movement for the levers.

With these and other objects in view which will appear as the description pro- 50 ceeds, my invention resides in the combination and arrangement of parts hereinafter described and set forth in the claims.

In the accompanying drawings wherein I

have shown a convenient embodiment of my invention,

Fig. 1 is a vertical section through a portion of a Knowles head, the box actuating levers being indicated in rear elevation,

Fig. 2 is an enlarged rear elevation of the compound levers showing fragmentary parts 60 of the actuating vibrator levers,

Fig. 3 is an enlarged vertical section on line 3—3 of Fig. 1,

Fig. 4 is a detail horizontal section on line 4—4 of Fig. 2,

Fig. 5 is a diagrammatic view showing the color slide or selector and the means by which the same is controlled according to my invention, and

Fig. 6 is a fragmentary top plan taken in 70 the direction of arrow 6, Fig. 1 and showing the manner of locating the compound levers on the ordinary frame of the Knowles head.

Referring to the drawings it will be seen 75 that I have shown a loom arch 10 to which is secured a head frame 11 having oppositely rotating mutilated upper and lower actuating cylinders 12 and 13, respectively. The frame 11 supports a heel pin 14 on which 80 is mounted for limited angular movement a set of vibrator levers 15, two of said levers being shown herein for a 4 x 1 loom. A heel shell 16 prevents upward movement of the right hand end of the vibrator lever 15 85 under action of pattern chain 17 which is given an angular motion each pick of the loom by a cylinder 18 driven by mechanism not shown but well understood. Said chain is composed of links some spaces of which 90 are blank and some spaces of which are provided with balls 19 located under the vibrator levers so that the latter may assume either of two vertical positions.

The left end of each vibrator lever has 95 rotatably mounted thereon as at 20 a vibrator gear 21 movable into operative relationship with either of the cylinders 12 or 13 depending upon the pattern chain, and each vibrator gear is attached as at 22 to a 100 vibrator connector 23, there being two connectors shown herein. Spring actuated drop weight levers 24 may be employed to move the pivot 22 to its proper position for both positions of the vibrator levers so that the 105 same may be properly locked.

The mechanism for controlling the boxes includes two levers, one indicated at 25 and being pivoted to the arch 10 at 26 and the other lever 27 being somewhat shorter and pivoted at 28 to the arch. The upper end of each of the levers 25 and 27 is connected to a vibrator connector 23 and the box lifter chain 29 is connected as at 30 to the lever 25. Said chain 29 is trained around a sheave 31 freely rotatable on the lower end of the lever 27, said chain being guided around sheave 32 toward the shuttle boxes. The levers and their operative contacts with the chain 29 are such that the latter can be given four positions depending upon the positions of the vibrator connectors 23. The matter thus far described is the well-known Knowles head and may be substantially as shown in patent to Knowles No. 134,992.

20 In Fig. 5 I have shown diagrammatically a portion of a multi-color weft replenishing mechanism including a magazine 33 on which are mounted for vertical sliding movement a plurality of sliding controllers 34 which are provided with upper and lower lugs 35 and 36, respectively. By means of so-called cradles indicated at 37 the controllers regulate the movement of the bobbins from the magazine toward a common transfer position under said controllers.

25 The movements of the controllers 34 are determined by a color selector 38 longitudinally slidable in bearings 39 and having a pair of fingers indicated at 40 in dotted lines. A bell crank lever 41 pivoted as at 42 to the magazine has connection by means of a grooved collar 43 with the color slide 38 and a rod 44 pivotally connected to the lever 41 and having a compression spring 45 therearound and interposed between an arm 46 of the magazine and the lever 41 tends to move the latter to the left as shown in Fig. 5.

30 It is desirable that the color selector 38 be given a position to correspond with the active shuttle and when there is a change in the shuttles there must be a corresponding change in said selector so that one or the other of the fingers 40 will be operatively related to the controller 34 which corresponds to the active shuttle. By means of mechanism not shown but set forth in my earlier Patent No. 1,030,748 the color selector is given an angular movement so that 35 one of the fingers 40 will have operative contact with the lug 35 or 36 corresponding to the shuttle requiring replenishment. The mechanism described in connection with Fig. 5 is well understood and for a further description of the same reference may be had to my aforesaid patent.

35 As previously stated when the multi-color weft replenishing mechanism has been used on a loom employing the Knowles head it 40 has been customary to have the color selec-

tor 38 actuated directly by the box lifter chain 29, but in fast running looms employing the Knowles head it is found that this connection moves the color selector too slowly so that it starts to have its angular movement before its longitudinal movement is completed with the result that an improper movement of one or another of the controllers 34 follows.

45 It is the general object of my present invention to introduce between the Knowles head vibrator 15 or some part connected therewith and the color slide 38 appropriate mechanism to complete the movement of the latter before the box lifter chain 29 comes to rest. Accordingly, in carrying out my invention I provide a small stand 50 secured to one of the sides of the head frame 11 as shown in Fig. 6 and provide said stand with a fixed stud 51 as shown in Figs. 3 and 4. Said stud has pivoted thereon two actuating levers, one of which, indicated at 52, has an upwardly extending arm provided with a stud 53 and a horizontally extending foot 54 which rests on an extension 55 of one of the vibrator levers 15. The other lever 56 has a depending arm which supports a stud 57 and a horizontally extending foot 58 which rests on another extension 59 projecting upwardly from the other of the vibrator levers 15. A control lever 60 is pivoted substantially at the central portion thereof on the stud 53 of the lever 52 and has a slot in the lower end thereof for the stud 57 of the lever 56. The upper end of said control lever 60 has attachment with a connector 61 which may be connected in any approved manner to the bell crank lever 41 as by passing over a guide sheave 62 rotating on a fixed center. The connection 61 acts against the force of spring 45.

50 In the operation of the loom the pattern chain 17 will present balls and blank spaces under the vibrator levers 15, according to the pattern desired, and the extensions 55 and 57 will be raised and lowered in predetermined order. The levers 52 and 56 can therefore give four different positions to the studs 53 and 57, thus moving the upper end of lever 60 to four different positions. The levers 52, 56, and 60 constitute a system of compound levers by means of which the color slide 38 is moved in timed relation with the active shuttle.

55 It will be seen that the box lifting chain 29 does not start its movement until the vibrators and the levers 52 and 56 have completed their movement and it is at a still later time that said chain 29 reaches its final position for any given pick. It will thus be seen that the connector 61 completes its movement well in advance of the completion of the movement of the boxes which are actuated by the chain 29 so that the color selector 38 can be properly placed earlier

than has been possible heretofore in looms employing the Knowles head.

From the foregoing it will be seen that I have provided means for bringing the color slide of a multi-color weft replenishing mechanism to rest prior to the completion of the movements of the levers of the Knowles head which control the movements of the boxes. While I have shown the system of compound levers as actuated by direct contact with the vibrator levers 15, yet I do not wish to be limited to this construction. The invention set forth herein is also applicable on the so-called Knowles side plate box motion shown in Patent No. 551,104 to Wattie and Hutchins.

Having thus described my invention, it will be apparent that changes and modifications may be made therein by those skilled in the art without departing from the spirit and scope of the invention, and I do not wish to be limited to the details herein disclosed but what I claim is:

1. In a weft replenishing loom having a multi-color magazine and a color selector therefor, a pair of spaced actuating cylinders, a vibrating element comprising a lever, a gear rotatable thereon, and a vibrator connector operatively connected to the gear, shuttle box actuating mechanism operatively connected to the connector, a pattern mechanism to give the lever a complete movement prior to the actuation of the shuttle box controlling mechanism by the connector, and means connected to the selector and actuated by a portion of the vibrating element, whereby the selector is given a complete movement before the movement of the shuttle box controlling mechanism is completed.

2. In a weft replenishing loom having a multi-color magazine and a color selector therefor, a pair of actuator cylinders, pattern mechanism, a vibrator lever interposed between the cylinders and operatively related to the pattern mechanism to be given a plurality of positions by the latter, shuttle box actuating devices operatively connected to the vibrator lever and actuated by the cylinders after the vibrator lever has been positioned by the pattern mechanism, and means actuated by the vibrator lever during the movement thereof by the pattern mechanism to control the position of the color selector prior to movement of the shuttle box actuating devices.

3. In a weft replenishing loom having a multi-color magazine and a color selector therefor, a shuttle box actuating mechanism, a pattern mechanism, vibrator levers to be actuated by the pattern mechanism and movable thereby to a plurality of positions, means operative after the vibrator levers have been given a complete movement by the pattern mechanism to actuate the shuttle box mechanism, and devices operatively

connected to the vibrator levers and movable thereby as the same move under influence of the pattern mechanism to position the color selector, said selector receiving a complete movement prior to the movement of the shuttle box actuating mechanism.

4. In a weft replenishing loom having a multi-color magazine and a color selector therefor, a shuttle box controlling mechanism, a pattern mechanism, vibrator levers for the pattern mechanism movable by the latter, means to actuate the shuttle box controlling mechanism after the vibrator levers have been given a complete movement by the pattern mechanism, and means operatively related to the vibrator levers and effective during the time that said levers are being moved by the pattern mechanism to control the position of the color selector, whereby said selector receives a complete movement before the shuttle box controlling mechanism completes its movement.

5. In a weft replenishing loom having a multi-color magazine and a color selector therefor, a pattern mechanism, a shuttle box controlling mechanism, a vibrating element connected to the shuttle box controlling mechanism and having a portion thereof under control of the pattern mechanism to be given a plurality of positions by said pattern mechanism, a pair of rotating actuating cylinders, a rotary member forming part of the vibrating element and interposed between the portions of the latter which are operatively related respectively to the pattern mechanism and the shuttle box controlling mechanism, and means connected to the selector and movable by a part of the vibrating element to give said selector a complete movement before movement of the shuttle box controlling mechanism.

6. In a weft replenishing loom having a multi-color magazine and a color selector therefor, a pattern mechanism, a vibrator lever therefor, a vibrator gear mounted on the vibrator lever, a pair of oppositely rotating spaced actuating cylinders, a vibrator connector attached to the gear, a box motion actuating mechanism operatively connected to the vibrator connector, said vibrator lever and gear being movable to a plurality of positions relatively to the operating cylinders by the pattern mechanism, and a lever actuated by the vibrator lever and operatively connected to the color selector to give the latter a complete movement prior to the completion of the movement of the shuttle box controlling mechanism by the vibrator connector.

7. In a weft replenishing loom having a multi-color magazine and a color selector therefor, a pattern mechanism, a pair of vibrator levers therefor, a vibrator gear for each vibrator lever, a pair of spaced actua-

tor cylinders, said pattern mechanism moving the gears into operative relationship with respect to either cylinder for actuation, a vibrator connector for each vibrator gear, 5 a shuttle box controlling mechanism operatively connected to each vibrator connector, and a system of compound levers operated by the vibrator levers and attached to the color selector to give the latter a complete 10 movement prior to the completion of the movement of the shuttle box actuating mechanism.

8. In a weft replenishing loom having a multi-color magazine and a color selector 15 therefor, a pattern mechanism, a pair of vibrator levers therefor, a vibrator gear for each vibrator lever, a pair of spaced actua-

tor cylinders, said pattern mechanism moving the gears into operative relationship with respect to either cylinder for actuation, 20 a vibrator connector for each vibrator gear, a shuttle box controlling mechanism operatively connected to each vibrator connector, and a system of compound levers operated by the vibrator levers and attached to the color selector to give the latter a complete 25 movement prior to the completion of the movement of the shuttle box actuating mechanism, said compound levers having a lever for each vibrator. 30

In testimony whereof I have hereunto affixed my signature.

EPPA H. RYON.
